Frank Davis INVENTOR.

UNITED STATES PATENT OFFICE.

FRANK DAVIS, OF BROOKLYN, NEW YORK.

NOISE-MAKING ALARM.

Application filed July 30, 1925. Serial No. 47,037.

This invention relates to improvements in alarms and more particularly to sound alarms, and has for its object to provide a simple, inexpensive and highly efficient sound alarm capable of delivering a noise-making signal adequate to convey a distress communication at a relatively great distance from the location of the alarm.

Another object of the present invention 10 is to provide a sound alarm mechanism wherein use is made of two sound intonators, bells or the like, the cumulative ringing of which results in producing a louder, more distinct and harsher sound than either alone, especially where the sound producer is in 15 continuous operation, as is contemplated by the present invention.

A still further object of the present invention is to provide a burglar and hold-up 20 alarm or fire alarm designed to be rendered audible at greater distance than is now found practicable by ordinary sound producers. In carrying out the present invention it is proposed to employ a motor preferably an electrical motor with suitable connections to operate a clapper which engages 25 oscillatingly with two sound intonators, of preferably different timbre, size and inflection, thereby combining the two sounds in a louder sound. The rapid revolutions made 30 per minute by the motor results in motion being imparted sharply and abruptly to the clapper which responds with blows repeatedly made upon the two intonators.

35 A still further object of the present invention is to provide in connection with a sound producer or intonator means for delivering a steady, rapid, loud, and alarm-conveying signal powerful enough to attract instant attention whenever it is heard, and thereby serving to bring succor and aid to distressed people in any office, shop, or building in which the alarm may be stationed.

With the above and other objects in view 45 my invention consists in the combination, construction and details disclosed in the specification and drawings and then more particularly pointed out in the appended claims.

50 In the drawings which are merely illustrative of my invention and in which similar

reference characters designate similar parts throughout the respective views,

Figure 1 is a side elevation, partly in section of the parts of my invention, 55

Figure 2 is a perspective view of my invention,

Figure 3 is a vertical sectional elevation thereof,

Figure 4 is a perspective view of the 60 clapper operating mechanism, and

Figure 5 is a detail fragmental view of the housing wherein is shown a part of the clapper actuating mechanism. 65

In the drawings 10 designates a suitable 65 baseboard made preferably of insulating material, and 11 indicates two uprights of a frame or support secured upon the opposing ends of said baseboard. Connecting longitudinally the uprights is a horizontal 70 bar 12 upon which are operatively suspended preferably two sound intonators, bells, or inverted metal drums, one intonator being bigger, and harsher in sound than the other and of a different timbre, so that the sounding of both of them at the same time by a rapidly operating striker is calculated to produce a louder resultant noise, sufficiently prolonged to cause an alarm, for any desired 75 purpose. 80

The bells 13 and 14 are separated apart leaving a space 12^a in which means projects for engaging both bells to ring them; said means being a striker or clapper 28 hereinafter described. Bolts 15 and securing nuts 85 16 serve as the means of fastening the drums upon the frame bar 12. A suitable motor, preferably an electrical motor 17 is also secured down upon the baseboard and is included in an electrical circuit adapted to be 90 closed as by a switch (not shown). The motor shaft 18 is capable of undergoing several thousand revolutions per minute, and carries a crank pin 19 upon which is pivoted a connecting rod 20 which is pivotally connected by its bifurcated portion or arm 21 at 22 to a reciprocating member or slideable actuator 23 which is suitably dovetailed or otherwise slidably guided in a housing or guide 23^a mounted upon a pedestal 29 secured upon the baseboard 10. A bent lug 24 is secured flat against the plunger or slide- 95 100

able member 23 and carries an arm 25 at right angles with respect to the housing 23^a. Secured in upwardly extending relation upon the end of arm 25 is a clapper or striker 6 of resilient metal terminating at its uppermost extremity in a ball or other impact making part 28; this ball being designed to alternately and successively engage and strike both bells 13 and 14, when in operation.

10 The device is strongly built with a frame 30 projecting immediately above the ball 28 of the clapper to assure the proper release of the sound waves between both bells and 15 to interrupt the waves so as to cause a blunt noise to ensue.

Suppose this alarm to be located in an office equipped with suitable circuit makers, and that the latter are operated upon the 20 happening of some unexpected nefarious doing such as a hold-up during daylight. Instantly the circuit is closed to the motor 17 which immediately rotates shaft 18 causing the slidable actuator 23 to be rapidly 25 and repeatedly successively reciprocated for the purpose of in turn reciprocating the arm 25 and with it the clapper arm 27, causing the clapper ball to rapidly vibrate and alternately strike the bells 13 and 14, merging 30 their sounds in one blunt, savagely loud distinct noise audible at great distances from the scene of the hold-up and serving thereby to convey an effective alarm to policemen or others who may be attracted to the office 35 where help is quickly needed.

I claim all mechanical changes coming within the purview of the appended claims.

What I claim and seek to protect by Letters Patent is:—

40 1. In an alarm mechanism, a pair of spaced sound producers, a slidably reciprocable actuator beneath said sound producers, means for guiding the movements of said actuator, an upstanding resilient striking arm carried by said actuator substantially at the middle thereof to extend upwardly between said sound producers, said arm having 45 an impactor on its free end, a power driven crank and connecting arm for operating said actuator whereby the reciprocation thereof rapidly vibrates said resilient arm to forcefully move said impactor in alternate sounding contact with said sound producers.

50 2. In an alarm mechanism, a pair of spaced sound producers, a slidably reciprocable actuator beneath said sound producers, means for guiding the movements of said actuator, an upstanding resilient striking arm carried by said actuator to extend upwardly between said sound producers, said arm having an impactor on its free end, a comparatively high speed electric motor having 55 a crank member in connection with its armature shaft, a connecting rod between said crank member and said actuator, all

whereby said actuator is rapidly reciprocated to vibrate said resilient arm and forcefully move said impactor in alternate sounding contact with said sound producers.

3. In an alarm mechanism, a pair of spaced sound producers, a reciprocable actuator beneath said sound producers to move in horizontal plane, guide means for said actuator, an upstanding resilient striking arm carried by said actuator substantially at the middle thereof to extend upwardly between said sound producers and arranged to vibrate in vertical plane, said arm having an impactor on its free end, and means for rapidly reciprocating said actuator to in turn vibrate said striking arm whereby said impactor is forcefully carried in alternate sounding contact with said sound producers.

4. In an alarm mechanism, a pair of spaced sound producers, a reciprocable actuator beneath said sound producers to move in horizontal plane, guide means for said actuator, an upstanding resilient striking arm carried by said actuator to extend upwardly between said sound producers and arranged to vibrate in vertical plane, said arm having an impactor on its free end, a comparatively high speed electric motor having a crank member in connection with its armature shaft, a connecting rod between said crank member and said actuator, all whereby said actuator is rapidly reciprocated to vibrate said resilient arm and forcefully move said impactor in alternate sounding contact with said sound producers.

5. In an alarm mechanism, a base, a frame-work rising from said base, a pair of gong-like sound producers suspended from said frame-work above said base and spaced slightly apart, a reciprocable actuator beneath said sound producers, guide means mounted on said base to operatively mount said actuator for reciprocable sliding movement in horizontal plane, an upstanding resilient striking arm carried by said actuator substantially at the middle thereof to extend upwardly between said sound producers and arranged to vibrate in vertical plane, said arm having an impactor on its free end, and means for rapidly reciprocating said actuator to in turn vibrate said striking arm whereby said impactor is forcefully carried in alternate sounding contact with said sound producers.

6. In an alarm mechanism, a base, a frame-work rising from said base, a pair of gong-like sound producers suspended from said frame-work above said base and spaced slightly apart, a reciprocable actuator beneath said sound producers, guide means mounted on said base to operatively mount said actuator for reciprocable sliding movement in horizontal plane, an upstanding resilient striking arm carried by said actuator to extend upwardly between said sound pro-

ducers and arranged to vibrate in vertical plane, said arm having an impactor on its free end, a comparatively high speed electric motor having a crank member in connection with its armature shaft, a connecting rod between said crank member and said actuator, all whereby said actuator is rapidly re-

ciprocated to vibrate said resilient arm and forcefully move said impactor in alternate sounding contact with said sound producers. 10

In witness whereof he has hereunto set his hand this eleventh day of July, 1925.

FRANK DAVIS.
